COMBINED BRACKET, AIR FILTER AND GANG VALVE ASSEMBLY FOR HOME AQUARIUMS

David D. Lovitz, Short Hills, N.J., assignor to Sternco
Industries, Inc., Harrison, N.J., a corporation of New
Jersey

Filed Aug. 20, 1969, Ser. No. 18,769

Term of patent 14 years

Int. Cl. D23—01

U.S. Cl. D23—4

FIG. 1

FIG. 2

FIG. 3

FIG. 4

FIG. 5

FIG. 6

FIG. 7

FIG. 8

FIG. 9

FIG. 1 is a perspective view of a combined bracket, filter and gang valve assembly showing said new design with the gang valve member in one of two alternative positions.

FIG. 2 is a front view thereof.

FIG. 3 is a side view thereof, the opposite side view being identical.

FIG. 4 is a rear view thereof.

FIG. 5 is a top view thereof.

FIG. 6 is a bottom view thereof.

FIG. 7 is a front view of said combined bracket, filter and gang valve assembly showing the other of said two alternative positions of the gang valve.

FIG. 8 is a side view thereof.

FIG. 9 is a rear view thereof.

The aquarium is fragmentarily shown in broken lines in FIG. 1 for illustrative purposes only.

I claim:

The ornamental design for a combined bracket, air filter and gang valve assembly for home aquariums, as shown and described.
